UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

AUTOMATIC SWITCH.

1,238,194.

Specification of Letters Patent. Patented Aug. 28, 1917.

Application filed December 27, 1916. Serial No. 139,087.

To all whom it may concern:

Be it known that I, JOHN NEWBERRY REYNOLDS, a citizen of the United States, residing at Greenwich, in the county of Fairfield and State of Connecticut, have invented certain new and useful Improvements in Automatic Switches, of which the following is a full, clear, concise, and exact description.

This invention relates to telephone switch mechanisms, and more particularly to improvements in switch mechanisms shown in my Patent No. 1,131,734, March 16, 1915, in which circuit connections are established through the agency of two sets of relatively movable contact members carried by movable bars termed trunk and line bars. The trunk bars are arranged to be selectively displaced to bring their contacts into position to be engaged by contacts upon a line bar. The engagement between contacts of an operated line bar and trunk bar causes said trunk bar to be swung to a position where the contacts will be out of engagement with contacts of subsequently operated line bars. In the switch shown in the Patent No. 1,131,734 there is an individual operating magnet for each line bar.

The object of this invention is to simplify the structure and improve the operation of such switches.

In accordance with the general features of this invention, there is provided a common operating bar for the line bars with a single magnet, which in the operation of the switch is operated to move the common operating bar.

The drawing is a perspective view, with parts broken away, of a switch embodying the features of this invention.

Referring to the drawing, 1 represents a frame, only portions of which are shown. The trunk bars (of which only one is shown), are pivotally mounted in the top and bottom of the frame. Each trunk bar comprises a tubular member 2, to one side of which are firmly secured strips of insulation alternated with strips of conducting material or contact members 3. Each contact member carries a plurality of contacts 4 which are arranged in sets with the contacts of the other members on the same bar. Each tubular member has an extension 5 which forms an armature of a magnet 9, individual to each trunk bar, for displacing the con-

tacts of said trunk bar into an operative 55 position.

Line bars 6—6, which are adapted to cooperate with these trunk bars, are made in skeletonized form and each comprises a pair of side-supporting members between which are located the current conducting members. The conducting members are separated from each other and from the side-supporting members by means of insulating strips. Projecting from each of the conducting 65 strips are the contacts 7—7.

One end of a line bar 6 is supported by a simple pivoted link 10, one end of which is attached to the line bars by a pivot pin 12', and the other to the frame 1 by the pivot pin 12. At the opposite end of the line bar there is a link 11, pivotally mounted to the frame 1 by means of a pivot pin 13. One end of the link 11 is attached to the line bar 6, while another end thereof is provided with 75 a pin 37. A swinging plate 14 is mounted on this pin and arranged to be rotated against the action of spring 15 by means of a rod 16 attached to an armature 17 of a line magnet 8 to move said plate into a 80 position to be engaged by an arm 50 of a common operating bar 18. The common operating bar 18 is arranged to be moved longitudinally in the frame 1 by a common bar magnet 19. Magnet 8 in attracting its armature, closes a circuit for the common bar magnet 19, which attracts its armature and moves the common operating bar 18 upward. The bar 18 engages the plate 14 which has been operated by a line magnet and moves 90 the line bar, associated with this plate 14, inwardly and upwardly into engagement with contacts of a displaced trunk bar.

Link 11 is provided with an extension arm 21 which serves as an armature of a holding magnet 22 when the line bar is in its operative position. Magnet 22, when energized, serves to keep the arm attracted, thereby keeping the line bar in its operated position.

The operation of the switching mechanism embodying the features of this invention is briefly as follows: A preselected trunk bar will be set or moved to a displaced position by reason of the energization of its individual setting magnet 9, and will be locked 100 in such displaced position temporarily in the well-known manner. Then, when a subscriber at substation A takes his receiver

from the hook, a line magnet 8 corresponding to said substation will become energized over the following circuit: grounded battery, line magnet 8, conductor 23, springs 24 and 25, conductor 26, telephone apparatus at the substation A, conductor 27, springs 28 and 29 to ground. Relay 8 attracts its armature 17, which positions the plate 14 of the line bar individual to the calling line. Armature 17 closes the springs 30 and 31, which completes the following circuit: grounded battery, springs 30 and 31, conductor 32, common bar magnet 19 to ground. Magnet 19 attracts its armature 20 which moves the common operating bar 18 upward. By this movement of the bar a projection 50 engages the positioned plate 14 corresponding to the calling line, and causes the line bar 6 associated therewith to be moved inwardly and upwardly to bring contacts thereon into engagement with contacts of the displaced trunk bar, and also to bring arm 21 of the lever 11 into operative relation with magnet 22. Upon the engagement 25 of the contacts of the operated line bar with the contacts of a displaced trunk bar, a circuit for holding magnet 22 is completed as follows: grounded battery, resistance 33, conductor 34, inner contact member 3, inner 30 left-hand trunk contact 4, inner left-hand line contact 7, conductor 35, magnet 22 to ground. Magnet 22 becomes energized and retains arm 21 in its operated position. Arm 21 in its operated position opens the contacts 28, 29 and 24, 25, thereby opening the circuit of relay 8. This relay 8 deenergizes and its armature in falling back opens the circuit of the common bar magnet 19 at springs 30 and 31. The common operating 40 bar is thereby returned to normal and is in readiness to establish another connection.

Upon the calling subscriber hanging up his receiver at the termination of the conversation, the current of magnet 22 is interrupted and the deenergization of the magnet allows the arm 21 to drop by means of its own weight and spring 15 to its normal position, thus returning the line bar and the terminals thereon to their normal positions.

50. What is claimed is:

1. In a connecting switch, a plurality of trunk bars, contacts on said trunk bars, a plurality of line bars, contacts on said line bars arranged to engage the contacts of said trunk bars, means for displacing each of said trunk bars into position to have its contacts engaged by contacts of said line bars, and an operating bar common to all of said line bars for moving a line bar into an operative position to engage with its contacts the contacts of a displaced trunk bar.

2. In a connecting switch, a plurality of trunk bars, contacts on said trunk bars, a plurality of line bars, contacts on said line bars arranged to engage the contacts of said

trunk bars, means for displacing each of said trunk bars into position to have its contacts engaged by contacts of said line bars, an operating bar common to all of said line bars for moving a line bar into an operative position to engage with its contacts the contacts of a displaced trunk bar, and an electromagnet for operating said operating bar. 70

3. In a connecting switch, a plurality of trunk bars, contacts on said trunk bars, a plurality of line bars, contacts on said line bars arranged to engage the contacts on said trunk bars, means for displacing each of said trunk bars into position to have its contacts engaged by contacts of said line bars, an operating bar common to all of said line bars for moving a line bar into an operative position to engage with its contacts the contacts of a displaced trunk bar, and means individual to each line bar for associating it with the common operating bar. 75

4. In a connecting switch, a plurality of trunk bars, contacts on said trunk bars, a plurality of line bars, contacts on said line bars arranged to engage the contacts on said trunk bars, means for displacing each of said trunk bars into position to have its contacts engaged by contacts of said line bars, an operating bar common to all of said line bars for moving a line bar into an operative 80 position to engage with its contacts the contacts of a displaced trunk bar, and means individual to each line bar for associating it with the common operating bar. 85

5. In a connecting switch, a plurality of trunk bars, contacts on said trunk bars, a plurality of line bars, contacts on said line bars arranged to engage the contacts of said trunk bars, means for displacing each of said trunk bars into position to have its contacts engaged by contacts of said line bars, an operating bar common to all of said line bars for moving a line bar into an operative 90 position to engage with its contacts the contacts of a displaced trunk bar, and a magnet individual to each line bar for associating it with the common operating bar. 95

6. In a connecting switch, a plurality of trunk bars, contacts on said trunk bars, a plurality of line bars, contacts on said line bars arranged to engage the contacts of said trunk bars, means for displacing each of said trunk bars into position to have its contacts engaged by contacts of said line bars, an operating bar common to all of said line bars for moving a line bar into an operative position to engage with its contacts the contacts of a displaced trunk bar, an electromagnet for operating said operating bar, 100 and means individual to each line bar operated when said line bar reaches its operative position for holding said line bar in its operative position and for releasing said operating bar. 105

7. In a connecting switch, a plurality of trunk bars, contacts on said trunk bars, a plurality of line bars, contacts on said line bars arranged to engage the contacts of said trunk bars, means for displacing each of said trunk bars into position to have its contacts engaged by contacts of said line bars, an operating bar common to all of said line bars for moving a line bar into an operative 110 position to engage with its contacts the contacts of a displaced trunk bar, an electromagnet for operating said operating bar, and means individual to each line bar operated when said line bar reaches its operative position for holding said line bar in its operative position and for releasing said operating bar. 115

8. In a connecting switch, a plurality of trunk bars, contacts on said trunk bars, a plurality of line bars, contacts on said line bars arranged to engage the contacts of said trunk bars, means for displacing each of said trunk bars into position to have its contacts engaged by contacts of said line bars, an operating bar common to all of said line bars for moving a line bar into an operative 120 position to engage with its contacts the contacts of a displaced trunk bar, an electromagnet for operating said operating bar, and means individual to each line bar operated when said line bar reaches its operative position for holding said line bar in its operative position and for releasing said operating bar. 125

9. In a connecting switch, a plurality of trunk bars, contacts on said trunk bars, a plurality of line bars, contacts on said line bars arranged to engage the contacts of said line bars, an operating bar common to all of said line bars for moving a line bar into an operative position to engage with its contacts the contacts of a displaced trunk bar, an electromagnet for operating said operating bar, and means individual to each line bar for controlling said electromagnet. 130

7. In a connecting switch, a plurality of trunk bars, contacts on said trunk bars, a plurality of line bars, contacts on said line bars arranged to engage the contacts of said 5 trunk bars, means for displacing each of said trunk bars into position to have its contacts engaged by contacts of said line bars, an operating bar common to all of said line bars for moving a line bar into an operative 10 position to engage with its contacts the contacts of a displaced trunk bar, a swinging plate associated with each line bar, an electromagnet individual to each of said line bars for displacing the plate associated with 15 the corresponding line bar, projections on said common operating bar arranged to engage the displaced plate, and an electromagnet for operating said common operating bar.
- 20 8. In a connecting switch, a trunk bar, contacts on said trunk bar, a line, a movable line bar connected to said line, contacts on said line bar arranged to engage contacts of said trunk bar, means actuated upon the initiation of a call on said line for moving 25 said line bar to engage with its contacts the contacts of said trunk bar, and means operated upon the engagement of said contacts for holding said line bar in its operated position.
9. In a connecting switch, a trunk bar, contacts on said trunk bar, a line, a movable line bar connected to said line, contacts on said line bar arranged to engage contacts of said trunk bar, means actuated upon the initiation of a call on said line for moving said line bar to engage with its contacts the contacts of said trunk bar, an arm connected to said line bar arranged to disconnect said first mentioned means when said line bar 30 reaches its operated position, and means operated upon the engagement of said contacts for holding said line bar and said arm in their operated position.

In witness whereof, I hereunto subscribe 45
my name this 26th day of December, A. D.
1916.

JOHN NEWBERRY REYNOLDS.
